CLAIM

The ornamental design for a vehicle taillamp, as shown and described.

DESCRIPTION

FIG. 1 is a front and left side perspective view of a vehicle taillamp showing our new design;

FIG. 2 is a front elevation view thereof;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings illustrate portions of the vehicle taillamp forming no part of the claimed design. The broken lines illustrating a lens that cross over the front of the vehicle taillamp illustrate environmental subject matter and form no part of the claimed design. The claim includes a second embodiment comprised of a mirror image of the vehicle taillamp as shown in FIGS. 1-7.
